UNITED STATES PATENT OFFICE.

CHARLES N. BATT, OF WATERFORD, NEW YORK, ASSIGNOR OF ONE-HALF TO JOHN T. CHAPMAN, OF ALBANY, NEW YORK.

FOLDING-MACHINE.

1,091,557.

Specification of Letters Patent. Patented Mar. 31, 1914.

Application filed May 7, 1913. Serial No. 766,082.

To all whom it may concern:

Be it known that I, CHARLES N. BATT, a citizen of the United States of America, residing at the village of Waterford, in the county of Saratoga and State of New York, have invented certain new and useful Improvements in Folding-Machines, of which the following is a specification.

My invention relates to feeding mechanism for folding machines, and the object of my invention is to provide an auxiliary guide for the purpose of conducting sheets of paper or similar material to the place for operation; together with such elements and combinations as are hereinafter more particularly set forth and claimed. I accomplish these objects by means of the mechanism illustrated in the accompanying drawings, in which:

20 Figure 1 is a plan of my invention attached to the machine. Fig. 2 is a section along the line 1—1 on Fig. 1. Fig. 3 is a side elevation of my guide, with parts broken away. Fig. 4 is a plan of the guide. 25 Fig. 5 is a section along the line X—X on Fig. 3. Fig. 6 is a section along the line Z—Z on Fig. 3.

Similar letters refer to similar parts throughout the several views.

30 A, represents a table made up of a series of rollers, B, B, placed diagonally across the table, as shown in Fig. 1, and such as is in common use in folding machines whereby the sheets of paper, 3, that are placed upon 35 the table, A, are, by the rotation of the rollers, B, B, gradually brought against one side, C, of the table where they are caused to assume a proper position on the table and are passed from the table over the parallel 40 rollers, B', B'; (which are placed at right angles to the axis of the table) to the folding mechanism, T, in proper position for folding, so that they may be folded alike without further manipulation as to their relative position.

In order to increase the output from the table, A, especially where small portions of a sheet are used, I have invented a guide, H, which I secure about midway between the 50 sides of the table in such a manner that those papers, 4, which are placed on the table at the right of the guide, H, will, by the rotation of the rollers, B, B, be brought into alinement against the guide, H, while

55 those papers that are placed at the left of

the guide, H, will, by the rotation of the rollers, B, B, be brought into alinement against the guide, C, as heretofore. Thus there can be twice as many papers delivered to the folding mechanism, T, than when the 60 guide, H, is not used.

The guide, H, is preferably made up of an angle plate, J, attached to a plate, K, by means of a series of suitable screws, I, passing through the slotted openings, j, in the angle plate, J. I attach to one end of the guide, H, a curved bar, M, carrying a plate, N, which is provided with a clamping means, O, for securing the plate, N, to the folding mechanism. In order to adjust the guide, H, I place the screw, m, through a slotted opening, n, in the angle plate, J, whereby the bar, M, may be rotated on the screw, p, which passes through a circular opening in the angle plate, J.

75 The clamping means, O, is comprised of two bell crank levers, S, S, attached to the underside of the plate, N, and adapted to engage the strips, t, t, of the folding mechanism and be held in connection therewith by the screw, U, forced downward upon the ends of the bell crank levers, causing them to grip the strips, t, t. The springs, f, tend to return the levers, S, S, to their former position after the screw, U, is released.

80 For the purpose of securing the end of the guide, H, opposite that to which the plate, N, is secured, I arrange a curved bracket, V, engaging the bottom of the plate, K², attached to angle plate, J, which will permit the end of the guide, H, to be placed on the stationary plate, D, by placing the plate, K², on the table and pressing the bracket, V, under the table, which will be held in position by the screw, v, which passes through a slotted opening, v', in the plate, K², and which is adjusted by the screw, W, which engages the plate, D. The lower edge of the plate, K, is cut out diagonally at k, k', for the purpose of permitting the plate, K, to come 90 close to the rollers, B, B, and to allow for the uninterrupted revolution of the diagonally placed rollers, B, B. At one end of the guide the lower edge is curved at k', k', in the portion, K', of the guide, H, for the purpose of permitting the rotation of the rollers, B', B', which extend across the table at right angles to the axis of the table.

100 I do not wish to limit myself to the particular means for attaching the guide or 110

holding it in position and I have simply shown a very practical way of accomplishing this result without attempting to limit myself to that construction.

5. What I claim as my invention and desire to secure by Letters Patent is:

1. In a device for guiding sheets of paper, a table provided with a series of diagonally placed rollers; a guide at one side of said 10 table; an auxiliary removable guide placed over said rollers provided with diagonal grooves along its sides adjacent to said rollers and into which a portion of said rollers may project; and means for attaching said 15 auxiliary guide in any desired position between the sides of the table.

2. An auxiliary guide for a table for carrying and arranging in proper position for folding sheets of paper, comprising two 20 plates, one of which overlaps and projects beyond the other; a curved bar secured at one end of the guide; clamping means comprising two bell crank levers adapted to en-

gage portions of the folding mechanism; a screw adapted to press the legs of the bell 25 crank levers apart and grip said portions; with an adjustable means at the opposite end of said guide for attaching to the stationary table.

3. In a feeding mechanism for folding 30 machines, an auxiliary guide provided along one side with a series of grooves; a table provided with a series of rollers; said auxiliary guide placed over said rollers in such position that the rollers shall rotate partially within said grooves; means for attaching said guide at one end to the folding machine; and means for attaching the other end of said guide to the table. 35

In testimony whereof I have affixed my 40 signature in presence of two witnesses.

CHARLES N. BATT.

Witnesses:

GRACE PRIOR,
FREDERICK W. CAMERON.
